COMBINED BASSINET AND CHEST

Shafie Saba, Toledo, Ohio, assignor to Paul Darah,
Toledo, Ohio

Application April 14, 1955, Serial No. 35,518

Term of patent 14 years

(Cl. D5—5)

FIG. 1-

FIG. 2-

FIG-4-

FIG-3-

Figure 1 is a front elevational view of a combined bassinet and chest embodying my new design;

Figure 2 is an isometric view of the combined bassinet and chest;

Figure 3 is an end view, and

Figure 4 is a top plan view of the combined bassinet and chest.

The characteristic features of the design reside in the portions shown in full lines.

What I claim is:

The ornamental design for a combined bassinet and chest, substantially as shown and described.
